UNITED STATES PATENT OFFICE.

LOUIS DEJONGE, JR., OF STAPLETON, NEW YORK.

MACHINE FOR COATING PAPER OR LIKE MATERIAL IN SHEETS AND DRYING SAME.

SPECIFICATION forming part of Letters Patent No. 533,443, dated February 5, 1895.

Application filed January 31, 1894. Serial No. 498,578. (No model.)

To all whom it may concern:

Be it known that I, LOUIS DEJONGE, Jr., of Stapleton, in the county of Richmond and State of New York, have invented certain new and useful Improvements in Machines for Coating Paper or Like Material in Sheets and Drying the Same, of which the following is a full, clear, and exact description.

My invention relates to a machine for coloring or coating sheets of paper, or like material, and likewise a machine whereby the colored or coated sheets may be dried.

The object of the invention is to provide a machine wherein sheets of paper or like material will be automatically clamped to a carrier, conveyed to the color-carrying and applying mechanism, held from buckling when coated, automatically released from the carrier at a given point in its travel, and automatically elevated when released, whereby the colored and coated sheets may be mechanically removed from the carrier.

A further object of the invention is to provide a machine wherein wet sheets may be automatically removed from the coloring or coating section and made to travel through any desired number or runs, even when one run is above or beneath the other, the travel through the runs being accomplished automatically, the sheets hanging in a pendent position throughout the entire drying operation.

Another object of the invention is to so construct the carriages or conveyers for the sheets that they may be arranged close together without interfering one with the other, and to provide a clip for the carriages or conveyers which will not injure the sheets as they automatically grip them, and from which the sheets may be conveniently and expeditiously released.

Another object of the invention is to provide a means whereby when the sheets are removed from their carriages or conveyers, the latter will be automatically directed to the coloring or coating section of the machine and automatically receive another sheet or sheets to be dried; and a final object of the invention is to provide for the coating and the drying of the sheets without in the least marring the uncoated surface if the coating is upon one side only.

The invention consists in the novel construction and combination of the several parts, as will be hereinafter fully set forth, 55 and pointed out in the claims.

Reference is to be had to the accompanying drawings forming a part of this specification, in which similar figures and letters of reference indicate corresponding parts in all the 60 views.

Figure 1 is a side elevation of the coloring machine, and a side elevation of one end of the drier. Fig. 2 is a side elevation of the drier, showing both the front and rear ends 65 thereof, the central portion being broken away. Fig. 3 is an enlarged side elevation of the coloring section of the machine. Fig. 4 is an enlarged cross section of the cylinder adapted to carry the paper to be colored, the 70 section being likewise taken through the distributing brushes and through the color-applying mechanism. Fig. 5 is a section taken practically on the line 5—5 of Fig. 6, representing one end portion of the cylinder and 75 adjacent mechanism, and illustrating in particular the mechanism for holding the ends of the sheet to be colored to the cylinder. Fig. 6 is a front view of the mechanism shown in Fig. 5. Fig. 7 is a view similar to that shown 80 in Fig. 5, showing the paper held fast to the drum by the clamping mechanism, Fig. 5 representing the clamp open to receive the sheet. Fig. 8 is a view similar to Figs. 5 and 7, illustrating the clamp in contact with the sheet, 85 and the trip mechanism nearing the point at which the sheet is to be released. Fig. 9 is a view similar to Fig. 8, illustrating the shifting mechanism as having been operated upon, the clamp removed from the sheet, and 90 the sheet lifted at the end formerly clamped. Fig. 10 is a sectional view of the cylinder as represented in Fig. 9, illustrating in detail the lifting device for the paper. Fig. 11 is a perspective view illustrating how the conveyer 95 or carriage sticks adapted to carry the colored sheets are transferred from one run to the other in the drying section of the machine. Fig. 12 is a plan view of the coloring section of the machine, and a portion of the drying section adjacent to the coloring section, being practically a plan view of that portion of the machine shown in Fig. 3. Fig. 13 is a sectional detail view, illustrating the manner in which

the clips of the stick carriage or conveyer are opened to receive the ends of the paper after the paper has been colored and is leaving the machine. The said view shows also in dotted lines the clips in a closed position, grasping the ends of the sheet and traveling upward to the drying section of the machine and removing the sheet from the coloring section thereof, and the section is taken on the line 13—13 of Fig. 12. Fig. 14 is a detail view of the conveyer or carriage sticks, illustrating the same as traveling upward to the drier section, and the clip of the stick in a horizontal position, the sheet being nearly removed from the coloring section of the machine. Fig. 15 is a longitudinal section of one end of the conveyer or carriage stick. Fig. 16 is an end view of the drying section of the machine, said view being made upon a large scale. Fig. 17 is a longitudinal vertical section of the drying section of the machine, taken practically on the line 17—17 of Fig. 16. Fig. 18 is a longitudinal vertical section of what may be termed the rear end of the drier, or the end opposite that illustrated in Figs. 16 and 17; and Fig. 19 is a detail view, showing a portion of the main conveyer of the drying section of the machine, and a stick carriage or conveyer in section upon the main conveyer. Fig. 20 is a perspective view illustrating the manner in which the carrier sticks are guided upward during the time of receiving and after they have received the colored sheets. Fig. 21 is a detail view partially in side elevation and partially in section of one of the carrier sticks, illustrating a slight modification in the construction of the clips; and Fig. 22 is a transverse section through the stick and through one of the clips.

I will first describe the construction and operation of the mechanism employed for coloring or coating the paper, next the mechanism for drying the same, and finally the connection between the coloring and drying mechanisms.

In the matter of the coloring mechanism, a hollow cylinder A, is mounted to revolve in a frame B. The frame may be of any desired shape, but as illustrated it consists of front standards 11 and rear standards 12 joined together. The standards of each set are connected by suitable cross bars or tie rods, and the two sets of standards are usually connected by an upper side or bed bar 13, ordinarily located at or near a central point between the ends of the standards and a bottom side bar 14. The shaft 15 of the cylinder A, is journaled in bearings 16, carried by the rear set of standards above the bed bar, best shown in Fig. 3, and the ends of the cylinder are in a measure closed or protected by segmental extensions 12^a of the rear standards. The cylinder preferably consists of a metal body 17, securely attached to the shaft 15, and a facing 18 of wood, papier-maché or equivalent material; but at one point in the circumference of the cylinder the casing is cut away

from end to end, producing a recess or space 19. The cylinder is revolved by producing or locating a gear 20 at for example its right-hand end, which gear meshes with a pinion 21, upon a drive shaft 22, journaled in the rear standards of the frame. A driving pulley 23, is shown as secured to the right-hand end of the drive shaft to be connected by means of a belt 24 with any source of power. A second and larger pulley 25, is located at the opposite end of the shaft, adapted to drive portions of the mechanism, usually distributing brushes.

A pad 26 of rubber or equivalent material is made to cover a portion of the outer or circumferential face of the cylinder, and is removably secured to said surface. The pad is adapted as a bed or platen for the sheet to be colored, and consequently is of sufficient size to support the entire surface of the sheet to be operated upon. The pad, although shown as extending to the end of the drum may terminate at any desired distance from the end. One end of the pad is located close to the walls of the recess or space 19 in the cylinder, and the attachment between the pad and cylinder is usually made through the medium of screws, as shown in Fig. 6, although other means may be employed. A bar 27, is secured to the cylinder in the recess 19 at that end contiguous to the pad; and this bar, as shown particularly in Figs. 4 and 10 is provided with a series of pins 28, which pins extend through the bar, suitable apertures 29 being produced to receive them. The apertures are made wide enough between their ends to form chambers for the reception of springs 30. The springs are usually coiled around the pins and connected with them in such manner that the upper ends of the pins are normally held flush with the top surface of the bar, and the lower ends a predetermined distance below the under surface of the bar, as shown in Fig. 4.

The pins may be termed lift pins, since the portions of the sheet to be clamped rest upon the pins; and when that portion of the sheet is released from its clamp or clamps, the pins will be automatically acted upon, and will raise the said portion of the sheet from the cylinder, enabling it to pass freely to a table or other receptacle near the cylinder, as shown in Fig. 10. The pins are actuated through the medium of a series of fingers 31, located within the cylinder and secured upon a shaft 32, journaled in suitable bearings within the cylinder and extending usually from end to end of the latter. An angle arm or cam 33, is secured preferably upon the left-hand end of the finger shaft 32, which end extends beyond the end of the cylinder, as shown in Figs. 5 and 6.

When the clamped portion of the sheet arrives at the point at which the sheet is to be discharged, and just after the clamping mechanism employed is removed from the sheet, the angle arm or cam is brought in contact

with a stud 34, projected inwardly from the frame extension 12^a, as shown in Figs. 6 and 9. As the cylinder revolves the angle arm or cam in passing the pin will rock the finger shaft 5 in a manner to force the fingers against the lower ends of the lift pins, force the outer ends of the said pins outward and thereby lift the paper resting upon the pins, as shown in Fig. 10. When the angle arm or cam 33 10 has passed the stud 34, the fingers will gravitate to their normal position, and the pins being released will be returned by their springs to their normal position.

It will be understood that any desired number 15 of pins may be employed, and that a finger 31 is provided for each pin; also that any equivalent of the angle arm or cam 33 and the stud 34 may be substituted therefor.

The clamp employed to hold the sheet to be 20 treated consists of a plate 35, which is preferably of the same length as the pin-carrying bar 27, since the plate when in clamping position is supported at one edge by the said bar, and that surface of the bar upon which 25 the plate is to rest is beveled, as shown at 36 in Figs. 7, 8 and 9. The clamping plate is secured to a shaft 37, journaled in bearings 38, projected from the pin-carrying bar 27, the shaft and bar being parallel; and a pinion 39, is secured preferably to the left-hand end of the shaft. The pinion 39 meshes with a second pinion 40, secured upon the inner or right-hand end of a short shaft 41, journaled in bearings located upon the body of the cylinder 35 in the recess 19. The left-hand end of the shaft 41 extends some distance beyond the end of the cylinder, as shown in Fig. 6, being securely fastened to the central portion 40 of a cross head 43, having forked or bifurcated extremities, designated respectively as 43^a and 43^b. The cross head may be termed a shifting head, as it is employed to effect a change in the position of the clamping plate.

One end of a rod 44, is eccentrically and 45 pivotally connected with the shifting cross head, the attachment being made nearer one side edge, between the connection of the head with its shaft 41 and one of the forks, the fork 43^a, for example. At its opposite end and intermediate of its ends the rod 44, is held to 50 slide in bearings 45, located upon the left-hand end of the cylinder, which end is wholly or partially closed; and a spring 47 encircles the rod between its bearings, and a collar 46 55 contained upon the rod, the spring being so attached to the rod as to cause the latter to exert constant pressure upon the shifting cross head in an outwardly direction.

The shifting cross head assumes two positions, both tangential to the cylinder. In one 60 position the fork 43^b is the outer one, and in the second position the fork 43^a assumes that place. In the first named position of the shifting cross head the clamp is opened and held away from the pin-carrying bar, or the 65 pad, allowing the sheet to be moved away and another sheet placed in position to be

gripped; and in the last named position the clamp will hold the sheet upon the pad. The tension rod 44 acts to hold the shifting cross 7c head in the inner position.

The shifting cross head 43, is acted upon by two studs 48 and 49, secured to the left-hand extension 12^a of the frame, one of the studs, that designated as 49, being located at 75 the upper part of the frame extension upon a bracket 49^a, projected upward therefrom; and the other stud is placed near the lower end of the extension, as shown best in Fig. 6. The lower stud 48 is in the vicinity of an adjustable section 50^a of a feed table 50, the said feed table 50 being supported upon the frame by a cross bar 51, located upon the bed bars 13 of the frame, as shown in Fig. 3. The upper stud 49, is located adjacent to a receiving 80 table C, and both studs extend horizontally 85 from the extension of the frame in direction of the left-hand end of the cylinder.

In the operation of the clamping plate 35, supposing the plate to be in the open position 90 shown in Fig. 5, which figure represents the cylinder nearly ready to receive the sheet of material to be coated and which sheet is designated as D, the stud 48, will at that time have entered the fork 43^a of the shifting cross 95 head. As the cylinder revolves in the direction of the arrow in Fig. 5, the inner fork 43^a, or that engaged by the fixed stud 48, will be carried forward and the shifting pinion 40 will be turned in a direction to so move the 100 clamping pinion 39 that the clamping plate will be forced upon the sheet D if the latter is fed to the beveled surface 36 of the pin bar 27, as shown in Fig. 7. The closing of the 105 clamp takes place when the fork 43^a of the shifting head is the outer one, taking the position formerly occupied by the fork 43^b; and in this movement of the shifting cross head the tension rod will be thrown at the opposite side of the center of the said shifting head, and will 110 therefore hold the head in its changed position. The shifting cross head will remain in the position shown in Fig. 7, causing the clamping plate to hold the sheet until the sheet has received its coloring compound or coating, 115 and also until the point is reached when the sheet is to be delivered to the receiving table C, or removed from the cylinder. At this time the sheet is released from the clamp by the upper stud 49, entering the fork 43^b, which in 120 the revolution of the cylinder will be the forward one, as shown in Fig. 8. As the stud 49 acts upon the fork 43^b by the revolution of the cylinder, the shifting head is rocked until the fork 43^b is brought to the upper position 125 and the fork 43^a to the lower position, as shown in Fig. 9, and the clamp shaft is rocked in a direction to remove the clamp from the sheet, this position of the shifting head corresponding practically to its position at starting and shown in Fig. 5. As the cylinder 130 continues to revolve it carries the pad 26 downward, facing the front of the machine; and when the end of the pad at which the bar

27 is located approaches the adjustable section of the feed table 50^a, the beveled portion 36 of the pin-carrying bar 27, will engage with the projecting portion of a second sheet, 5 and at that instant the lower stud 48, will have acted upon the shifting cross head in such a manner as to close the clamp against the sheet, and another sheet is in position to be acted upon or coated, and to be released 10 at the upper portion of the machine, or wherever the releasing trip 34 may be located. The clamp being made in the nature of a blade will bear equally upon the entire surface of the paper with which it contacts; and the engagement of the clamp with the paper is such that it is an utter impossibility for the color, no matter how thin, to find its way at the back of the sheet, and in this manner the sheet at its back is preserved clean, and may 15 in its turn be coated or colored if desired. The feed table is provided with the movable section 50^a in order that the said section may carry the paper upward to meet the beveled surface 36 of the lift-pin bar.

25 Beneath the movable section 50^a of the feed table a shaft 52, is located in the frame, and the said shaft has claws 53 mounted upon it, adapted for engagement with the under surface of the said movable section of the table; 30 and an angular guide 54, is projected from the opposite side of the shaft, that is, in direction of the cylinder, the guide being preferably made integral with or attached to the claws, both moving together. A pitman 55, 35 is attached to the claws where the latter are mounted upon the shaft 52, the said pitman being shown best in dotted lines in Fig. 4. This pitman carries at its rear end a friction roller 56, which is adapted to be acted upon by 40 a cam 57, carried by the cylinder shaft 15. When the pitman 55 is in an upper position, being carried to that position by a spring or equivalent tension device, not shown, the claws will be removed from contact with the 45 feed table, as shown in Fig. 11, and the movable section 50^a of the table will be in a downwardly inclined position, while the guide 54 connected with the claws will be elevated in front of the rear end of the movable 50 section of the table, extending above its upper surface. Therefore when a sheet is placed upon the table it is fed rearward or in direction of the cylinder until the sheet strikes the guide 54, as is likewise shown in Fig. 11; 55 and prior to the action of the clamping plate 35 to clamp the sheet, the cam 57 will have depressed the pitman 55 and thus elevated the claws, depressing the guide 54 and elevating the rear end of the movable table section, 60 leaving the sheet extending beyond the rear end of that section to be caught by the clamping plate.

Beneath the cylinder A a table 58, is pivotally connected with the rear portion of the rear standards 12 of the frame, and the said table is provided with an arm 59, shown in Fig. 3, which extends downward and is con-

nected with a horizontal arm 60, the said arm extending within the body of the frame, and is held to slide upon a suitable support 61 located 70 preferably upon the left-hand bottom bar 14 of the frame, since the operator usually stands at this side of the machine in feeding. A treadle 62, carrying a cam 63, is pivotally mounted through the medium of said cam, 75 upon a shaft 64, also shown in Fig. 3. The cam is flattened at one side, the remaining exterior surface being cylindrical, and the cam is adapted for engagement with the arm 60. When the flat surface of the cam is in 80 engagement with the arm 60, the table 58 will drop downward a predetermined distance, and when the cylindrical surface of the cam engages with the inner end of the arm 60 the table will be carried upward in direction of 85 the cylinder, the cam holding the table in whatever position it may be placed. Any desired means may be employed for limiting the downward movement of the table, or it may have support other than that provided 90 by the cam.

The table 58 is adapted to support the color-carrying and applying mechanism, and if desired the table may be made removable 95 from the frame.

The color-carrying and applying mechanism in its entirety is designated by the reference letter E, and is best shown in Figs. 3 and 4. It comprises the following parts: A color box 65, provided with a double bottom forming a steam space 66, is located upon the table and adjustably connected therewith by means of a set screw 67, or an equivalent fastening device. A take-up roller 68, of any approved construction, is held to turn in the 100 color box 65, and it may here be remarked that the color box is practically of the same length as the cylinder. Hangers 69, are pivoted upon the trunnions of the take-up roller 68, or upon an equivalent support, one hanger 105 extending upward from each end of the color box, as shown in dotted lines in Fig. 4 and in positive lines in Fig. 3. Each hanger is provided at its upper end with a sliding box 70 and an adjusting mechanism 71, whereby the 110 box may be raised or lowered and held in its adjusted position. The trunnions of the distributing roller 72, are journaled in the said boxes 70, and the distributing roller is preferably of less diameter than the take-up roller, 115 and the two are adapted to run in more or less close contact. The distributing roller is held in position to bear to a greater or less degree upon the sheet to which the color is to be applied, preferably through the medium 120 of guide arms 73, having bearing against the hangers 69 of the distributing roller, said guide arms being screwed into brackets 74^b attached to the rear end portions of the table 125 58, as shown in Fig. 4. The arms 73 are rendered adjustable through the medium of nuts located at their inner ends. The hangers 69 are held against their guide arms 73 by springs 73^a attached to the upper portion of 130

the hangers and to the corresponding portions of the brackets 74^b, being secured to said brackets by adjusting screws 74, and the attachment between the springs and the adjusting or take-up screws is a removable one; but I desire it to be distinctly understood that other means may be substituted for regulating the tension between the distributing roller and the paper than those shown, although the spring and adjusting device illustrated are preferred owing to their simplicity and effectiveness.

Both the take-up and distributing rollers are driven from the cylinder, and the driving connection is effected in the following manner: A bracket 75, preferably of angular construction, is projected forwardly from the right-hand end of the color box 65. This bracket is provided with three pinions designated respectively as 76, 77 and 78. The pinion 78 meshes with the gear 20 of the cylinder and with the pinion 77; and the pinion 76 meshes with the pinion 77 and with a gear 79, formed preferably upon the right-hand end of the take-up roller 68, while the gear on the take-up roller meshes with a corresponding gear 80, located upon the distributing roller.

It will be observed that the entire color-applying device may be dropped at any time out of engagement with the cylinder by the manipulation of the treadle 62, and all that it carries may be adjusted to or from the cylinder as desired, and that the distributing roller may be adjusted to or from the take-up roller, and the distributing roller adjusted independently of other adjustments to or from the pad of the cylinder.

Brushes F, are employed to travel over the coated or colored paper and facilitates the distribution of the color thereon. These brushes may be of any approved construction and are reciprocated over the cylinder in direction of its ends. Four brushes are illustrated, but any desired number may be used, and they are located at intervals between a point at the upper front portion of the cylinder and a point above the color-applying mechanism E, as is best shown in Fig. 4. Two opposing slide-ways 81, are employed in connection with each brush, and the said slide-ways are secured to the extensions 12^a of the frame and project beyond the cylinder. Each opposing pair of slideways is connected by rods 82, and each slide-way is provided with a box 83, held to slide therein, each box being fitted with an adjusting screw 84, or its equivalent as shown in Fig. 3. A head block 85, preferably of angular construction is located near the inner side of each box 83, see Figs. 4 and 12; and each head block has secured to its vertical member two rods 86, which rods pass loosely through openings in adjacent boxes 83, whereby the head blocks have lateral sliding movement in their boxes. Opposing head blocks are connected by cross bars 87, attached to the horizontal members of the latter; and posts 88 are ordinarily used

to attach the backs of the brushes at their ends to the corresponding portion of the cross bars. When four brushes are employed they preferably derive movement from two pulleys 89 and 90, located upon the left-hand side of the machine, one pulley between each two slide-ways as shown in Fig. 3. These pulleys are carried by standards 91, represented as attached to the left-hand extensions 12^a of the frame. The pulleys 89 and 90, are driven by a large driving pulley 25 connected with them by a belt 92, and each pulley 89 and 90, is virtually a crank disk, since each carries upon its inner face an eccentrically located pin 93, as is best shown in Fig. 12. The driving connection between the pulleys and the brushes is effected by mounting upon each left-hand slide-way 81 a lever 94 of the angle or elbow type, and connecting one arm of each lever, by means of a rod 95, with the cross bar 87 of one of the brush-carrying frames. See Fig. 12. The opposite end of each lever 94 is connected by a link 96 with one of the crank pins 93, two links belonging to adjoining brushes being connected with each crank pin, whereby adjoining brushes will be reciprocated simultaneously in opposite directions.

It is very desirable that the sheets, after they have received their coating, or have been colored, should be kept straight and flat upon the cylinder pad to prevent them from buckling. To that end I locate boxes 97 between the slide-ways 81, as shown in Figs. 3 and 4, journal shafts 98 in said boxes, and secure friction wheels 99 upon the shafts in an adjustable manner. The wheels 99, are adapted to travel upon the sheets at or near their side edges, as more or less of a margin is always allowed.

With reference to the drying section of the machine, the body thereof consists of a frame of any desired length or width. Usually however, it is quite narrow or of comparatively great length. The frame is alike in construction on both sides, and as shown in the drawings consists of two spaced forward posts 100 and 101, extending from the floor to the ceiling or roof of an apartment, two similar intermediate posts 102 and 103, and a rear end post 105, having attached to its inner face an angular guide bar, producing a longitudinal channel 104^a, Fig. 18. A guide bar 106, preferably L-shaped in cross section, extends from the inner front posts of the frame to the inner one of the rear posts, being located a predetermined distance from the ceiling and attached to the inner faces of the posts. The two bars 106 constitute the upper run. The next lower run is shorter and consists of like guide bars 107, similarly secured but extending from the front post to the forward of the intermediate posts only, as shown in Fig. 2. The third and lower run is constructed of bars 108, shaped and secured in the same manner and practically the same length as the guide bars 107 and located beneath the latter guide bars, while a fourth run, constructed of guide bars

109 shaped like the other pairs is located at the bottom of the frame and extends from end to end thereof.

In the form of drier illustrated the three upper runs are intended for drying purposes, and the lowest for returning the sticks or other medium employed to carry the articles to be dried to the front of the drying section, from whence they are conveyed in a manner to be hereinafter described to the coloring section of the machine from which section they were taken.

An endless conveyer 110, travels over the horizontal members of the guide bars 106 of the upper run, one stretch of the conveyer resting upon said members, the other stretch being beneath them, as shown in Fig. 2. At the forward end of the upper guide bars 106, sprocket wheels 111, are located, supported by suitable hangers, and corresponding sprocket wheels 112, are located at the rear ends of said bars, being secured to shafts 113, journaled in the frame, which shafts carry gear wheels 114 at their outer ends. The conveyers 110, which are preferably constructed of endless chain belts, run over the said sprocket wheels, and the links of the chain are provided at predetermined intervals with pins or studs 115, standing at right angles to the links and in an upright position when the chains are upon the guide bars 106. The conveyer 116 of the next lowest run and which travels over the guide bars 107, is made preferably in two sections 116^a and 116^b. The section 116^a, is the longest section, and is made to pass over a sprocket wheel 117, one of which is journaled at the inner end of each guide bar 107.

The section 116^a of each conveyer 116, is made to pass over a second sprocket wheel 118, shown in dotted lines in Fig. 2, which sprocket wheel is fast upon a shaft 119, and the said shaft carries likewise a gear wheel 120. The shafts 119, are journaled in the frame near the inner posts 101 of the forward sets. One of the shafts 119, preferably the left-hand one, is also provided with a small pulley 121, and both of the shafts are provided in addition to the sprocket wheels 118, with a second sprocket wheel 122, as shown in Fig. 17. These additional sprocket wheels 122, receive one end of the shorter section 116^b of the conveyers 116, and the opposite end of this section of the conveyers passes over a sprocket wheel 123, journaled upon a hanger 124 projected from the forward portion of the frame, as is likewise shown in Fig. 17, in which view also an idle sprocket 125 is shown as engaging with the lower stretch of this section of the conveyer at or about its center, the idle sprocket being journaled upon a bracket 126, projected from the inner forward post 101. The idle sprocket wheel, and likewise the sprocket wheel 123, appear upon both sides of the frame. The guide bar 107 of this second run at its forward end is somewhat inclined for the purpose of communicating with a transfer mech-

anism F² through the medium of which the material carried by the conveyers 116, is conveyed to the upper conveyers 110.

The transfer mechanism F², is duplicated at each side of the machine as well as the conveyers; and at each side of the machine, between the forward ends of the upper conveyers 110 and the next lower conveyers 116, 70 hangers 127 are projected rearwardly from the forward posts or standards 100, and each hanger journals a shaft 128, and each of said shafts has mounted upon its outer end a gear wheel 129, while a lifting or transfer arm 130, 80 is secured about centrally upon the inner end of each of the shafts 128. Each transfer arm is provided with a recess at each end, the recesses facing in opposite directions, one of them being designated as 131 and the other 85 as 132.

A track 133, is secured upon the upper or horizontal section of the forward portion of each guide beam 107 of the second run-way, and the said tracks 133, are curved forwardly 90 and upwardly in the segment of a circle, being secured to the inner faces of the front uprights 100, and the upper ends of the tracks 133 are carried over and upwardly beyond the forward path of the upper stretch of the 95 upper conveyers 110, as shown best in Fig. 17, while a second track 134, is projected from the inner face of each front standard or upright 100, concentric with the upper portion of the outer track 133, the rear end of 100 the shorter track 134 being carried alongside of the sprocket wheels 111 supporting the forward ends of the conveyers 110. Thus whatever is carried by the lower conveyers 116 to the track 133, will by the revolution of the 105 transfer arm 130 be carried upward, as shown in Figs. 11 and 17, in engagement with the track 133 until the space between the tracks 134 and 133 is reached, whereupon the article carried will then be supported by the lower 110 and shorter track 134, until it can be received upon the upper stretch of the upper conveyers 110. It may here be observed that instead of transfer arms being employed to accomplish this transfer from one run to the 115 other, endless belts may be substituted if in practice it is found desirable, or any equivalents of the belts may be employed.

The drive shaft 135 of the drier is held to turn in bearings 136, preferably projected downward from the ceiling or an overhead support, and the drive shaft extends across the upper run from one side of the machine to the other, being provided at one end with a pulley 137, which pulley is connected by a 120 belt 138 with a main driving shaft 139, provided with a suitable pulley to receive the belt, and likewise a pulley to receive the belt 24 communicating motion to the coloring machine and above alluded to. At the opposite 130 end of the driving shaft 135 a smaller sprocket wheel 140 is secured, and the said sprocket 140, is connected by a link belt 141 with a sprocket 142, secured preferably upon the

left-hand end of a shaft 143, which extends from one side of the machine to the other above the second run, or the one next to the top. In Fig. 2 this shaft is shown as being supported upon the guide beams 107, while in Fig. 17 it is shown as being journaled in bearings attached to a third forward upright or standard 100^a. Either construction may be adopted. The shaft 143 carries at each of its ends a pinion 144, and these pinions mesh with the gears 120, carrying the sprocket wheels over which both sections of the conveyers 116 pass, and in this manner proper movement is given to both sections of the conveyers.

The shaft upon which the left-hand wheel 120, is secured has been described as being provided with a small sprocket 121. This sprocket 121 carries a link belt 145, which likewise passes over a small sprocket 146, which sprocket is secured upon the left-hand end of a shaft 147, journaled upon the forward upper portion of the frame, as shown in Figs. 2 and 17; and the shaft 147 extends from side to side of the machine. The shaft carries at each end a gear 148, and the gears mesh with the gears 129 of the forward transfer mechanism.

A third conveyer 149, is held to travel beneath the conveyer 116, upon and under each of the guide bars 108. In the drawings these conveyers 149, are the receiving conveyers, being adapted to take the article to be dried from the coloring machine. The conveyers 149, are each constructed in two sections, a long or forward section 149^a, and a short or rear section 149^b. The forward section of each conveyer 149 travels over a sprocket wheel 150, journaled in the front of the machine, while the rear ends of the sections travel over sprocket wheels 151, shown in dotted lines in Fig. 2 upon a shaft 152 located near the forward of the intermediate standards or uprights 102. Upon the same shafts 152 which carry the sprocket wheels 151, a second sprocket wheel 153 is secured at each side, and over these second sprocket wheels the forward ends of the shorter conveyer sections 149^b pass, the rear end of each of these sections being passed over sprocket wheels 154, journaled upon hangers usually attached to the rear intermediate uprights 103, as shown in both Figs. 2 and 18, while an idler sprocket wheel 155, engages with the lower stretch of each conveyer section, and the upper stretch is given somewhat of an upward and a rearward inclination. This inclination is given in order to meet another transfer mechanism F', by means of which the material carried by the conveyers 149, may be elevated to the next upper conveyer 116. This transfer mechanism is substantially identical with that which has been heretofore described. It consists of two shafts 156, located one at each side of the frame and journaled in hangers secured to the upright 103. Each shaft 156 carries upon its inner end a transfer arm 157,

provided with oppositely-facing recesses 158 in its ends. Each shaft 156 is likewise provided with a gear 159, and one of the shafts 70 is likewise provided with a pulley 160. An upwardly and forwardly curved segmental track 161, connects with the rear end of each guide bar 108, and is carried upward above the supporting surface of the next upper 75 guide bar 107, as shown in Fig. 18; and a second and concentric track 162, is attached to the inner face of each upright 103, the smaller tracks extending forwardly to meet the rear end of the conveyers 116 near which it is located. Thus in the operation of the machine the arms 157 will receive the material carried rearward by the conveyers 149 and will transfer said material to the conveyers 116 of the next run, and from that run the forward transfer mechanism F², will convey the material to the conveyers of the next run. Both sections of the lower conveyer 149 and the rear transfer mechanism receive movement from the drive shaft 135. To that end shafts 164, 90 are journaled at each side of the machine, carrying gears 165, meshing with the gears 159 on the shafts 156. The shafts 164 are likewise provided with sprocket wheels 166, each adapted to carry a belt 163, which belts 95 run over sprocket wheels 160^a located upon the rear shafts 152 of the lower conveyers 149; and both of said shafts 152, are provided with a gear 160^b, which gears mesh with pinions 160^c, located at opposite ends of a shaft 160^d, 100 extending from side to side of the machine. The shaft 160^d is driven by a link belt 167, driven by the main shaft 135, and passed over a sprocket wheel at the left hand end of the shaft 160^d, as shown in Fig. 2. 105

Shafts 168, are journaled in the lower rear portion of the frame at each side, and a vertical conveyer 169, is passed over sprocket wheels 170 located upon the shafts 168, and over sprocket wheels 171, located upon the upper shafts 113, which likewise carry the sprocket wheels supporting the rear portion of the upper conveyers. The rear stretches of the vertical conveyers 169, face the grooves 104^a in the sides of the rear portion of the machine; and the upper conveyers 110, and the vertical rear conveyers 169, are driven by the same mechanism and in the following manner: A line shaft 172, is located at about the rear central portion of the frame. This shaft carries a large pulley 173, and a smaller pulley adjacent to the larger one, as shown in Figs. 2 and 18. The larger pulley 173 is connected with the left-hand pulley 160 on the left-hand transfer shaft 156 by a belt 174, while the smaller pulley adjacent to the pulley 173 is connected with a larger pulley 176 by a belt 175, as shown in Fig. 2, and said pulley 176 is journaled upon a shaft or in bearings below the line shaft 172. The pulley 176 carries a smaller pulley 177, which is connected by a belt 178, with a pulley 179 located on a shaft 180, which extends from side to side of the machine at its upper rear

portion, over the upper rear gears 114; and the said shaft 180, carries two pinions, one near each end, which mesh with the said gears 114, and thereby impart movement to the upper shaft 113, carrying the supports for the rear end of the upper conveyer and the upper end of the rear vertical conveyer.

The conveyers are all constructed in the manner heretofore described; that is, with a series of pins 115 projecting from them, and all of the conveyers heretofore described move at the same rate of speed.

The material carried by the upper conveyers is to be removed from the sticks, or whatever carrier is employed, before the carriers reach the rear vertical conveyer; and to that end a platform 181, shown in Fig. 18, is erected at the rear portion of the machine within the frame, and upon which the operator may stand and remove the sheets D from the carriage. The vertical conveyers will then conduct the carriers downward, the carriers being guided in their downward movement through the medium of the grooves 104^a, and will deliver the carriers to the return conveyer 182, traveling over the lower guide bars 109 from front to rear of the frame. The return conveyers 182, are alike in construction to the conveyers heretofore described, but they have the same speed as the machine to which they are to deliver the article carried by them.

The lowermost conveyers 182 travel over sprocket wheels 183 located at the rear of the machine, and over like wheels located at the lower forward portion of the machine upon a shaft 184, which shafts likewise carry sprocket wheels 185, supporting conveyers 186, serving to establish a return connection between the conveyers 182 and the coloring machine.

It is necessary, in the event the carriers or sticks should become diagonally located on the upper conveyers 110, that they should be straightened before they are received by the vertical conveyers 169; and to that end, as shown in Fig. 19, the upper guide bars 106, are provided near their rear ends with a cam plate 187, and when a stick reaches these plates, the end that touches a plate first will remain at the plate until the opposite end has been forced against the corresponding plate, and the fingers 115 of both of the upper conveyers are in engagement with the stick, whereupon the fingers will force the stick upward over the cam plates, carrying them down again upon the guide bars 106 to be received by the descending fingers of the vertical elevator, and when so received the ends of the stick will enter the guide grooves 104^a.

The preferred form of carrier is a stick G, a portion of which is shown in detail in Fig. 15. The stick comprises a body portion 188, and two end sections 188^a, which are pivotally connected with the body section through the medium of pins 189. The body section of the stick is adapted to carry clamps or clips H, adapted to receive paper after it is colored and hold the paper practically in a vertical

position while it is being conducted to the drier and while it is being carried from the drier. The clips H, are adjustably secured upon the body of the stick in order that they may be moved toward or from one another to receive and properly hold sheets of different widths. The preferred form of clip is that shown in Figs. 11 and 15, comprising a shank 190, which is made to pass upward through a slot 191, made longitudinally in the stick, the upper end of the shank being threaded to receive a wing nut 192, or its equivalent. The lower end of the shank has formed upon it a jaw 193, and the upper portion of the jaw is provided with a bearing 194, in which a pivot pin 195 is journaled, the said pin serving to pivot a second and movable jaw 196. This jaw is opened upon moving the pivot pin, which is spring controlled, in one direction, the pivot pin being operated through the medium of a crank arm 197, formed at one end, or its equivalent, the spring of the pivot pin serving to normally hold the jaws in a closed position. It is evident, therefore, that as the ends of the stick or carrier are pivotally connected with the body, and as the body is employed to carry the sheet, when the ends of the stick are supported upon guides, no matter in what position the guides may be, the body of the stick with its sheet will be free to turn and hang in such manner as to keep the sheet perpendicular; and it may here be stated that in the event it is found desirable, webbing or the equivalent thereof may be located beneath the conveyers in such a position as to receive and support the sheets, thus preventing them from buckling or curling during the process of drying.

In Figs. 21 and 22 I have illustrated another form of clip, designated as H', which clip may be termed a gravity clip, and comprises a yoke-like body 198, having sliding engagement with the body of the stick; and at each end of the yoke a jaw 199, is pivoted, the said jaws being capable of opening upward within the yoke, in which position they separate, but when dropped downward to a horizontal position, which is their normal position, the opposing ends of the jaw will contact, if nothing is between them, and if a sheet is between them, as shown in the drawings, the sheet will be firmly held in place. In this form of clip, by pressing the sheet upward between the jaws, the sheet is fixed in position.

In Fig. 21 the entire stick or carrier is illustrated, partly in elevation and partly in section, and the guides which serve to adjustably connect the clips with the stick are designated by the reference numeral 200.

The connection between the drying section of the machine and the coloring section is effected in the following manner: The conveyer belt 186 connecting with the return conveyer belt 182 of the drier is carried upward over guide pulleys 201, located upon the forward extension of the frame of the coloring machine; and the said belt is carried horizon-

tally from the said extension to a point in front of the cylinder of the coloring machine, being at that end supported by a sprocket wheel 202. It will be understood that one of these conveyers 186 is at each side of the machine, and the upper stretch of each conveyor 186, is supported upon a guide bar 203, preferably L-shaped or angular in cross section. The sprocket wheels 202, are journaled upon side beams 204, which extend upward from the frame of the coloring machine, preferably to the ceiling or overhead support, as shown in Fig. 1, and meet upper side bars 205, which in their turn connect with side bars 206, carried downward to an engagement with the drying section of the machine at the forward ends of the guide bars 108 of the receiving run-way of the said drying section. The upper side bars 205, and the downwardly-extending rear side bars 206, are preferably angular in cross section in order that they may support the upper stretches of the conveyers, the upper conveyer being designated as 207 and the rear one as 208. The lower end of each rear conveyer 208, is passed over a sprocket wheel 209, journaled preferably upon the side bars 206, while the upper portions of the said conveyers 208, are passed over sprocket wheels 210, located at the junction of the side bars 205 and 206. A second sprocket wheel is mounted upon each shaft carrying the sprocket wheels 210, and these additional sprocket wheels support the rear end of the upper conveyer 207, while the front ends of the conveyer 207, are supported by sprocket wheels 211, as shown in Fig. 1, preferably located upon the side bars 204 nearest the coloring machine. Upon the same shaft with the sprocket wheels 211 other sprocket wheels are located, which support the upper end of a front conveyer 212, traveling parallel with the front side bar 204, the lower ends of the front conveyers 212 being supported by sprocket wheels located upon the shaft 213, journaled in bearings projected from the front end of the front side bars 204, the said shaft 213 being made to extend from one side of the machine to the other, as shown in Fig. 12. At one end of the shaft 213, a pulley 215 is located, which is connected by a belt 216 with a pulley 217, located upon a shaft 218, carrying a pinion 219, which pinion meshes with a like pinion 220, upon the drive shaft 22 of the coloring machine. In this manner all of the conveyers 207, 208 and 212, are driven, and the conveyer 186, adapted to return the stick, is likewise driven from the drive shaft of the coloring section of the machine. The belt 216, is illustrated as provided with a tension pulley 221.

At each side of the machine, interiorly of the front side bars 204, two guide tracks 222 and 223, are located, the guide tracks 222 being the outer ones. These tracks extend upward to an overhead support and preferably the full length of the rear side bars 204, and the upwardly extending portions of these

tracks 222, are inclined in direction of the drying section of the machine. The lower portion of each guide track 222 is made practically horizontal, and that section may be termed a foot section, it being at an angle to the straight or vertical body section, and the two sections are connected upon a curve. The foot sections of the outer guide rails 222 extend over the front end of the delivery conveyer 186, as shown in Figs. 13, 14, and 20, and these foot sections are preferably located over the horizontal members of the side bars 203, over which the elevators 186 travel, as shown in Fig. 14, so that the sticks carried by the elevators 186, will be delivered upon the foot sections of the outer guide tracks, and will, when delivered thereon, be engaged by descending fingers, or those on the forward stretch of the vertical elevator 212, since all of the elevators are of the chain type, and the links are provided with the fingers 115 heretofore alluded to.

The inner guide tracks 223 are located inside of the outer guide tracks 222, and are of like formation, their body sections being in advance of the body sections of the outer tracks and their foot sections above equivalent sections of the outer track; and the space between corresponding sections of each pair of tracks is just sufficient to receive the ends of the sticks, and the sticks being rectangular in cross section will be enabled to turn therein the length of the inner tracks 223. The inner tracks 223 terminate a predetermined distance above the upper plane of the cylinder of the coloring section of the machine, and the upper ends of the inner tracks are forwardly flared or bent.

When the sticks are carried up in engagement with the two sets of tracks, the pivoted ends of the sticks will rest upon the outer track while the body portion will rest upon the inner track; and the moment that the sticks are carried clear of the inner tracks 223 the body portion will be free to turn upon its pivots, the ends being held stationary, and permit the sheet carried by the body to assume a vertical position. In fact, the body can turn to accommodate itself to the position of the machine.

As the sticks are carried up between the two tracks 222 and 223, as shown in Fig. 13, the jaws of the clips are opened when said jaws are opposite the delivery table C. This delivery table, as shown in Fig. 12, consists preferably of a series of fingers 224, which are secured upon a shaft 225, fixed to the frame and extending from side to side thereof. At the ends of the rows of fingers, arms 226, are forwardly projected from the fixed shaft 225. These arms carry trip blocks 227 in substantially a vertical position, the rear faces of which blocks at their lower ends are beveled, the remaining portion of the rear face being preferably straight. As the sticks ascend between the two guide tracks 222 and 223, the crank arms 197 of the clips H will

strike the inclined or beveled portions of the trip blocks 227, and the jaws of the clips will be gradually opened, and will remain open until the said jaws are opposite the delivery surface of the table C, as shown in Fig. 13. The colored sheet from the cylinder will at that time be slid over the delivery table between the jaws of the clips, and the moment that the crank arms 197 leave the trip blocks 227, the jaws of the clips will close upon the sheet, and as the sticks travel farther upward the sheet will be drawn from off the cylinder, assuming practically the position shown in Fig. 14; and when, as heretofore stated, the stick clears the inner guide tracks 223, the body of the stick will turn in a manner to cause its clips to hang in a pendent or vertical position, and the clips will remain in this position during the entire process of delivering the sticks to the drier and carrying the sticks through the drier to be again returned to the coloring machine.

In Fig. 14 the stick is illustrated in positive lines, as just turning at its body portion, while in dotted lines a stick is shown as just entering between the guide tracks 222 and 223, while in Fig. 13, a stick is shown in positive lines in position to receive a sheet, and in dotted lines as having received the sheet, the jaws of the clips having closed upon it.

It will be understood that the material to be dried may be taken into the drier at the top and carried downward to successive runs, and the empty sticks or carriers may be returned to the coloring machine upon a direct line with the receiving table C, or substantially so, and further, any form of guide may be employed to direct a stick from one section of a conveyer to another when the conveyers are made in sections.

It will be understood that substantially the same mechanism may be employed for automatically releasing the sheet from the carriers that has been shown and described as adapted to open the clips to receive the sheets, or any approved releasing mechanism may be used for the purpose.

Having thus described my invention, I claim as new and desire to secure by Letters Patent—

1. In a coloring or coating machine, the combination with a rotary carrier adapted to support the material to be colored, of a clamp pivotally mounted upon the carrier and adapted to engage with the article carried, a gear connected with the clamp, a cross-head, and a gear carried by the cross-head and meshing with the clamp gear, a spring-controlled tension rod eccentrically connected with the cross-head and having movement upon the carrier, and trips located in the path of the cross-head and adapted for engagement with opposite ends thereof, substantially as shown and described.

2. The combination with the cylinder and the clamp thereon, of a series of spring-pressed pins having guided movement in the

cylinder and arranged in a line extending essentially transversely thereof, a shaft journaled in the cylinder, a series of fingers secured on the shaft and loosely engaging the inner ends of the said fingers, a cam upon the shaft, and a stationary stud or abutment located in the path of the cam and adapted for engagement therewith to rock the shaft and force the pins outward to lift the sheet off the cylinder, substantially as described.

3. In a machine for coloring or coating paper or like material, the combination, with a rotary cylinder, and a bed located thereon and adapted to support the material to be colored, of a series of spring-controlled pins located at one end of the bed, the outer ends of the pins being normally substantially flush with the outer surface of the bed, the inner ends of the pins projecting within the cylinder, a rock shaft journaled in the cylinder and carried thereby, fingers secured upon said shaft and adapted for engagement with the inner ends of the spring-controlled pins, a cam of substantially angular shape located upon one end of the rock shaft and extending beyond the end of the cylinder, and a stud secured upon a fixed support and located in the path of the cam and adapted for engagement therewith, whereby while the cam is in engagement with the stud the fingers of the rock shaft will be pressed against the pins and the pins forced outward to lift the material upon the bed, and whereby when the cam is passing the stud the cam through gravity will carry the shaft out of operative connection with the pins, substantially as and for the purpose set forth.

4. In a machine for coloring or coating paper or like material, a feed table having a pivoted section, a lift mechanism adapted for engagement with the pivoted section, means, substantially as shown and described, for operating the lift mechanism, and a guide carried by the lift mechanism, which when the table is in its depressed position is in advance of the delivery end of the table, and which when the table is elevated is carried below the table, as and for the purpose specified.

5. In a machine for coloring or coating paper and other material, the combination, with a revolving cylinder and means for holding the material thereon, of a color depositing apparatus, the same consisting of a color box, a take up roller held to revolve in the color box, means for adjusting the color box to and from the cylinder, a distributing roller having adjustable attachment with the take-up roller, and a tension device whereby the distributing roller may be made to bear more or less against the carrying surface of the cylinder, as and for the purpose specified.

6. In a machine for coloring or coating paper or like material, a color box, a pivoted support upon which the box is adjustably mounted, a shifting device or mechanism connected with the color box support, a take-up roller journaled in the color box, a distribut-

ing roller driven from the take-up roller and having vertically adjustable bearing above the take-up roller, and likewise laterally adjustable bearing, and a tension device where-
5 by the distributing roller is held in a pre-de-
termined position, substantially as shown and
specified.

7. In a machine for coloring or coating pa-
per or like material, the combination, with a
10 cylinder adapted to carry paper, and devices
for holding the paper on the cylinder and re-
leasing the same, of a color-applying mech-
anism, consisting of a table pivoted below the
cylinder, a treadle connected with the table,
15 and means for locking the treadle in shifted
position, a color box adjustably located upon
the table, a take-up roller carried by the color
box and driven from the cylinder, pivoted
hangers projected upward from the color box,
20 a vertically adjustable distributing roller
journaled in said hangers, and a tension de-
vice whereby the distributing roller may be
held in more or less close relation to the car-
rying surface of the cylinder, as and for the
25 purpose specified.

8. In a machine for coloring or coating pa-
per or like material, the combination, with a
revolving cylinder provided with a bed to sup-
port the material to be colored, and devices
30 for clamping the material and releasing the
same, substantially as described, of a color
applying mechanism, comprising a color box
adjustable vertically and laterally to or from
the cylinder, a take-up roller journaled in said
35 box, a distributing roller adjustable vertically
to and from the take-up roller, and laterally to
or from the cylinder independently of the
color box, and distributing brushes held to
reciprocate over the surface of the cylinder,
40 as and for the purpose specified.

9. In a machine for coloring or coating pa-
per or like material, the combination, with a
revolving cylinder provided with a bed to sup-
port the material to be colored, and devices
45 for clamping the material and releasing the
same, substantially as described, of a lift
mechanism driven from the cylinder shaft
and operating upon the feed table, the said
mechanism carrying a guide, a color discharg-
50 ing device, consisting of a color box adjust-
able vertically and laterally to and from the
cylinder, a take-up roller journaled in the
color box, pivoted hangers projected upward
from the color box, boxes adjustable in the
55 said hangers, a distributing roller journaled
in the said boxes and a tension device con-
nected with the distributing roller, distribut-
ing brushes held to reciprocate over the sur-
face of the cylinder, and guide rollers held to
60 revolve between the distributing brushes and
adapted to travel along the edges of the pa-
per being colored, substantially as shown and
described.

10. In a machine for coloring or coating pa-
65 per or like material, the combination, with a
revolving cylinder provided with a bed to sup-
port the material to be colored, clamping and

releasing mechanisms substantially as shown
and described, operating in the cylinder near
the bed and adapted for operation upon the
70 material to be colored, of a color-applying
mechanism, comprising a color box, a take-up
and a distributing roller, the latter being
adapted for contact with the article to be col-
ored, color-distributing brushes operating
75 upon the cylinder at a predetermined dis-
tance from the color-applying mechanism,
and guide rollers operating upon the edges of
the material to be colored, to hold the same
firmly upon the bed while the said material
80 is operated upon by the distributing brushes,
substantially as and for the purpose set forth.

11. In a machine for drying paper or like
material, a drier, the same consisting of a se-
ries of runs, each run consisting of one or
85 more conveyers, and a transfer mechanism
located between the runs, consisting of an
elevator connecting the runs, and a mechan-
ism for driving the elevator proportionately
to the speed of the conveyers, substantially
90 as shown and described.

12. In a machine for drying paper or like
material, a drier, the same consisting of a se-
ries of runs in which the material to be dried
is adapted to travel, and a transfer mechan-
ism connecting each two opposing runs, the
95 said transfer mechanism consisting of a re-
volving carrier, which receives the material
to be dried at one end of one run and deliv-
ers said material to the corresponding end of
100 the other run with which the transfer mech-
anism is in connection, as and for the purpose
specified.

13. In a machine for drying paper and like
material, a drier, the same consisting of a 105
framing, runs produced in the framing, each
run consisting of one or more endless con-
veyers, said conveyers being provided with
series of fingers as guides for the material to
be carried, and a transfer mechanism adapted
110 to convey the material from one run to the
other, each transfer mechanism consisting of
a revolving transfer arm having pockets re-
versely situated in each end, and a mechan-
ism, substantially as shown and described,
115 for driving the conveyers in the runs and the
transfer mechanisms, the latter being driven
at a proportionate rate of speed to that of the
conveyers, as and for the purpose set forth.

14. In a machine for drying paper and like
material, a drier comprising a frame, runs
formed in the frame, the runs consisting of
endless conveyers, and a transfer mechanism
located at the ends of the runs, between two
vertically opposing runs, said transfer mech-
anisms consisting of the guide track, curved
125 from one run over the run to which the trans-
fer is to be made, a second guide track curved
from the receiving run, or the one to which
the transfer is to be made, a predetermined
130 distance concentric with the free end of the
main or longer track, and a revolving trans-
fer arm centrally pivoted and provided with
pockets in its ends, the said arm being adapt-

ed to revolve adjacent to both of the tracks, receiving from one run and delivering to the other, the article received being guided by the tracks, as and for the purpose set forth.

- 5 15. In a machine for drying paper or like material, a drier consisting of a series of runs, each run comprising one or more endless conveyers, means for driving the conveyers, a transfer mechanism located between vertically opposing runs, comprising segmental guide tracks, a transfer arm held to revolve between the runs and in close proximity to the guide tracks, one guide track being made to emanate from each run, both guide tracks 10 being concentric and one longer than the other, carriers adapted to receive the material to be dried located upon the conveyers of the runs, a delivery conveyer to receive and deliver the carriers at the receiving end of the 15 drier, a vertical conveyer connecting the delivery conveyer with the conveyer of the last run in the drier, guides for the carriers located adjacent to the vertical conveyer, and a retarding mechanism located at the junction of 20 the vertical conveyer and the conveyer of the last run, as and for the purpose set forth.

16. In a drying apparatus, the combination, with a framing, a series of runs formed therein one over the other, one outer run being a receiving run and the other outer run a delivering run, each run consisting of one or more endless conveyers provided with guides thereon, and carriers located upon the conveyers and provided with clips adapted to receive 30 and hold the material to be dried, of a transfer mechanism located at the ends of the respective runs, each transfer mechanism being adapted to receive a carrier from the endless conveyer of one run and to deliver it to the 35 endless conveyer of the next run above or below, a discharge or delivery conveyer adapted to convey the carriers, when relieved of the material to be dried, to the receiving end of the drier, a conveyer likewise provided with 40 guides, connecting the conveyer of the discharge run with the delivery conveyer, and guide-ways located near the connecting conveyer, whereby the carriers will be held in 45 predetermined position, as and for the purpose set forth.

50 17. In a machine for drying paper or like material, a carrier, consisting of a stick adapted to receive a colored sheet, the said stick being provided with pivoted ends and 55 clips located upon its body portion, substantially as shown and described.

18. In a machine for drying paper or like material, a carrier adapted to receive a wet sheet, said carrier consisting of a stick constructed in three sections, a body section and two end sections pivotally connected with the body, and clips adjustably located upon the body section and adapted to receive and hold the colored sheets or material to be dried, as and for the purpose set forth.

65 19. In a machine for drying paper, or like material, a carrier stick, the same consisting

of a body section, and end sections pivotally connected with the body section, the end sections being adapted to be supported by a 70 conveyer, the body section being free, and clips located upon the body and adapted to receive the material colored or to be dried, said clips being automatic in their closing action and capable of receiving and holding 75 material passed through them, as and for the purpose set forth.

20. In a machine for drying sheets of paper or like material, a series of conveyers, transfer devices located between the conveyers, 80 and a carrier consisting of a stick provided with pivoted ends, and clips located upon its body portion adapted to receive the colored sheet or material to be dried, the ends of the stick being located upon opposing conveyers 85 and the body being free, whereby the clips may hang in substantially a vertical position, the pivoted ends of the stick being likewise engaged by the transfer device, as and for the purpose set forth. 90

21. In a machine of the character described, a carrier consisting of a stick provided with pivoted ends, and clips adjustably secured to its body portion, each clip consisting of a fixed jaw, a spring-controlled pivoted jaw, and a 95 crank arm controlling the pivoted jaw, as and for the purpose set forth.

22. In a machine for coloring or drying paper or like material, the combination, with a cylinder upon which the paper is colored, and a receiving table located adjacent to the cylinder, provided with trip arms connected therewith, of endless conveyers operating in front of the cylinder, the conveyers being arranged in pairs, carrier sticks located upon 100 the conveyers, each stick consisting of a body and ends pivotally connected with the body, the ends of the stick only being in engagement with the conveyers, clips carried by the body portion of the sticks, each of said clips being 105 provided with a fixed and with a spring-pressed jaw, and a crank arm controlling the spring-pressed jaw, the said crank arms being adapted for engagement with the trip arms of the receiving table, whereby the clips are opened 110 upon reaching the table and closed after passing 115 the table, as and for the purpose specified.

23. In a machine for coloring and drying paper, the combination, with a cylinder adapted as a support for the colored sheets, a receiving table located adjacent to the cylinder, and trip arms projected from the table, substantially as described, of a conveyer provided with guide fingers approaching the cylinder in a substantially horizontal direction, a second and similar conveyer located between the cylinder and the horizontal conveyer, the second conveyer being substantially vertically located, both conveyers being arranged in pairs, angular guide tracks of different 125 lengths, the longer ones being located with their horizontal members over the horizontal conveyers, the vertical members extending 130 upward, one parallel with each vertical con-

veyer, the shorter guide tracks being located with their horizontal members above and laterally removed from the corresponding members of the longer tracks, the vertical members of the shorter tracks being likewise removed from the vertical members of the longer tracks, thus forming a guide-way between the two, and carrier sticks having pivoted ends, the said sticks being delivered to the guide tracks by the horizontal conveyers and carried up the guide tracks by the vertical con-

veyers, the pivoted ends of the sticks only engaging with the longer guide tracks, while the body is in engagement with the shorter guide tracks, and clips carried by the body of the sticks, adapted to be opened by the trip arms of the receiving table, substantially as shown and described.
